(57) **CLAIM**

I claim the ornamental design for a bead apparatus, as shown and described.

DESCRIPTION

FIG. 1 is a perspective view of the bead apparatus; FIG. 2 is another perspective view of the bead apparatus; FIG. 3 is an end view of the bead apparatus; FIG. 4 is another end view of the bead apparatus; FIG. 5 is a rear side view of the bead apparatus; FIG. 6 is a front side view of the bead apparatus; FIG. 7 is a top view of the bead apparatus; FIG. 8 is a bottom view of the bead apparatus; FIG. 9 is a perspective view of another bead apparatus; FIG. 10 is another perspective view of the bead apparatus of FIG. 9; FIG. 11 is an end view of the bead apparatus of FIG. 9; FIG. 12 is another end view of the bead apparatus of FIG. 9; FIG. 13 is a rear side view of the bead apparatus of FIG. 9; FIG. 14 is a front side view of the bead apparatus of FIG. 9; FIG. 15 is a top view of the bead apparatus of FIG. 9; and, FIG. 16 is a bottom view of the bead apparatus of FIG. 9. The broken lines shown in the drawings depict portions of the bead apparatus that form no part of the claimed design.
